DESIGN FOR A MOP CLOTH

Ottolie Muckenhirn, Basel, Switzerland

Application February 9, 1938, Serial No. 75,022

Term of patent 14 years

To all whom it may concern:

Be it known that I, Ottolie Muckenhirn, a citizen of Germany, residing at Basel, Switzerland, have invented a new, original, and ornamental Design for Mop Cloths, of which the following is a specification, reference being had to the accompanying drawing, forming part thereof.

I claim:

The ornamental design for a mop cloth, as shown.

OTTOLIE MUCKENHIRN.
